UNITED STATES PATENT OFFICE.

EMILY W. THAYER, OF SHIRLEY CENTER, MASSACHUSETTS.

DESIGN FOR A HOSE-SUPPORTER BELT.

SPECIFICATION forming part of Design No. 31,331, dated August 1, 1899.

Application filed July 3, 1899. Serial No. 722,770. Term of patent 14 years.

To all whom it may concern:

Be it known that I, EMILY W. THAYER, of Shirley Center, in the county of Middlesex and Commonwealth of Massachusetts, have invented and produced a new and original Design for a Hose-Supporter Belt, of which the following is a full, clear, and exact description, reference being had to the accompanying drawings, in which—

10 Figure 1 is a plan view of the belt embodying my design, and Fig. 2 is a perspective view of the same upon a smaller scale and showing its appearance when in use.

15 The leading or material features of my design consist of the projections 3, formed at the lower edge of the belt 1 not far from the belt ends 2, the larger central projection or

enlargement 4, and the sweeping curves extending between the points 3 and 5.

The upper edge of the belt is unbroken, 20 and when the same is laid flat, as shown in Fig. 1, said edge is shaped as a segment of a circle.

Having fully described my invention, what I claim as new, and desire to secure by Letters Patent, is—

25 The design for a hose-supporter belt herein shown and described.

In testimony that I claim the foregoing invention I have hereunto set my hand this 26th day of June, 1899.

EMILY W. THAYER.
